UNITED STATES PATENT OFFICE.

HARVEY F. SEYBERT, OF BRADY'S BEND, PENNSYLVANIA.

MINER'S PICK.

SPECIFICATION forming part of Letters Patent No. 271,929, dated February 6, 1883.

Application filed September 20, 1882. (Model.)

To all whom it may concern:

Be it known that I, HARVEY F. SEYBERT, of Brady's Bend, in the county of Armstrong and State of Pennsylvania, have invented a new and useful Improvement in Miners' Tools, of which the following is a full, clear, and exact description.

My invention relates to picks and other tools used by coal-miners; and it consists in a spring-
10 handle, having the object to relieve the work-
man from the jar and shock of striking blows
with the tool, and also to insure more effect-
ive action by the tool, as set forth hereinafter.

Reference is to be had to the accompanying
15 drawings, forming a part of this specification,
in which similar letters of reference indicate
corresponding parts in all the figures.

Figure 1 is a perspective view of a pick with
my improvement applied. Fig. 2 is a side
20 view of the spring attachment. Fig. 3 is a lon-
gitudinal section, and Fig. 4 is a cross-section,
of the handle and spring.

The handle A of the pick is slightly reduced
in size at its outer end, and to that end is ap-
25 plied a spiral spring, B. The spring B is made
of strong wire and is wound closely, except at
the inner end, or the end passing upon the han-
dle, where two or three coils are separated
30 slightly in order that they may engage the
projecting pins *a* on the handle, by which the
spring is prevented from slipping off the han-

dle. The spring is shaped to the handle for
about two-thirds the length of the spring, and
its outer end increases slightly in diameter.
This enlarged end projects from the end of 35
the handle and assists in the holding of the
tool and increases the elasticity. This spring
may be applied to the handle of any tool, one
spring serving for a set. In use the spring
serves as the means by which the tool is held, 40
and when a blow is struck, instead of the force
being checked by the handle being held rig-
idly, the spring gives way at the same time
the hand and arm of the workman are relieved
from jar caused by the blow.

45 This device is inexpensive and can be readily
applied to mining and other tools.

Having thus described my invention, I claim
as new and desire to secure by Letters Patent—

1. In combination with the handle of a pick 50
or other analogous implement, a spiral-spring
extension which is adapted to snugly fit the
handle at its inner end, as and for the purpose
set forth.

2. The spiral spring B, formed with an en- 55
larged end and held upon the end of handle
A by pins *a*, as shown and described.

HARVEY F. SEYBERT.
